B. F. MERRITT,
INDICATING AND RECORDING APPARATUS,
APPLICATION FILED JUNE 21, 1915.

1,218,795.

Patented Mar. 13, 1917.

UNITED STATES PATENT OFFICE.

BENJAMIN FREDERIC MERRITT, OF EAST ORANGE, NEW JERSEY, ASSIGNEE, BY MESNE ASSIGNMENTS, TO WESTERN ELECTRIC COMPANY, INCORPORATED, A CORPORATION OF NEW YORK.

INDICATING AND RECORDING APPARATUS.

1,218,795.

Specification of Letters Patent. Patented Mar. 13, 1917.

Application filed June 21, 1915. Serial No. 35,410.

To all whom it may concern:

Be it known that I, BENJAMIN FREDERIC MERRITT, a citizen of the United States, residing at East Orange, in the county of 5 Essex and State of New Jersey, have invented certain new and useful Improvements in Indicating and Recording Apparatus, of which the following is a full, clear, concise, and exact description.

10 This invention relates to indicating and recording apparatus and its principal object is to produce an improved apparatus of the remote control type.

In accordance with its general characteristics the invention comprises a plurality of indicating or recording devices, such as character wheels, adapted to be controlled by groups of current impulses, each having an individual actuator operating from a common source of power. The actuators are 15 successively brought into operative relation to the corresponding indicating or recording devices during the intervals between the groups of impulses by controllers whose positions determine the condition of the actuators. This mechanism is combined with means for effecting the production of a permanent record.

This apparatus is particularly adapted for 20 fire alarm or police signal systems wherein a plurality of outlying stations, each designated by a characteristic number, may operate a central office indicator or effect the production of a permanent central office record.

25 It will be readily understood, however, that the apparatus and method of operation, to be hereinafter described, is readily applicable to many other uses as, for example, the indicating of subscribers' numbers in telephone systems.

The above and other objects of this invention will be fully set forth in the following description and claims, and will be more readily understood by reference to the 30 accompanying drawing wherein the circuit connections are shown diagrammatically and the apparatus is shown in perspective.

The indicating or recording devices comprise a plurality of character wheels 5, one 35 for each digit or portion of the desired indication or record, independently and loosely mounted upon a shaft 6. Each character wheel is provided with a spring 7, one end of which is secured to the character wheel, 40 the other end being fastened to the frame-

work so that as the wheels are rotated, in the direction of the arrow, to set up an indication or record, the springs are put under tension and may be utilized to return the 45 wheels to normal, as will be hereinafter explained.

Each character wheel 5 has secured thereto a ratchet wheel 8, which is adapted to be engaged by an individual actuator in the form of operating pawls 11, 12, 13, 14. 50 Pawls 11 to 14 inclusive are secured to and actuated by an armature 15 of an operating electromagnet 16, and are adapted to co-operate with controllers preferably in the form of cam wheels 21, 22, 23 and 24. These 55 cams are mounted upon and rotated by a shaft 25, which is provided at one end with a pinion 26 and at the other end with a gear wheel 27. The cams 21 to 24 inclusive are provided with flattened portions over a part 60 of their circumferences, and are so positioned relative to each other that these flattened portions successively come below a downwardly projecting lug 29 on the actuators 11 to 14 as shaft 25 is revolved in the 65 direction of the arrow. It is only while a lug is not resting on the cylindrical portion of a cam that the hooked end of its actuator is lowered sufficiently to cause the reciproca- 70 tion of the actuator to rotate the correspond- 75 ing character wheel. Normally the flattened portion of cam 21 lies beneath lug 29 of actuator 11.

Cams 21 to 24 inclusive are each like- 75 wise provided with a pin 30. These pins are 80 positioned beneath the flattened portions of the corresponding cams and are adapted to co-operate with a regulator or check mechanism for determining the time and extent of the movements of shaft 25. This check 85 mechanism comprises the checking pawls 31, 32, 33 and 34, each of which is provided with a downwardly projecting lug 35, and all of which are pivotally carried on the ar- 90 maturer 15 of electromagnet 16.

Cams 21 to 24 inclusive are rotated in the direction of the arrow at the proper time by a spring 40, through the agency of a lever 41, pivoted on an axis 42, and provided with a sector 43 whose teeth engage pinion 105 26. Spring 40 tends to rotate lever 41 about its axis 42 in the direction of the arrow, but normally this movement is prevented by the engagement of a spring tensioned latch 44 pivoted at 45 to an extension of lever 41 110

and hook 46 secured to the framework. The engagement between latch 45 and hook 46 may, however, be broken upon the receipt of current impulses, since a lateral extension 47 of latch 44 is adapted to be engaged by armature 15.

A downwardly extending portion of lever 41 is provided with three contacting extensions 50, 51 and 52. Extension 50 is adapted, under conditions to be presently explained, to close a switch 53, one element of which is connected to a grounded source of energy 54. Extension 51 momentarily effects the closure of switch 55, one element of which is connected to a grounded source of energy 56, and extension 52 normally produces an open condition in a switch 57, which, however, becomes closed when projection 52 is removed from engagement with one of its elements by the movement of lever 41 in the direction of the arrow.

The rotation of cam shaft 25 by spring 40 through the intermediate elements is controlled by a speed regulating escapement system comprising a pinion 60, whose teeth engage gear wheel 27, a ratchet wheel 61 secured to pinion 60, and an escapement wheel 62 with which a weighted verge 63 cooperates. A spring tensioned pawl 65 forms a link between escapement wheel 62 and ratchet wheel 61, so that during the movement of cam shaft 25 in the direction of the arrow the rotation is governed by the escapement system, while, when the cam shaft 35 is rotated in the opposite direction in the restoration of the apparatus, the movement is free from the influence of the escapement system, and the return movement may be very rapid. This restoring action is accomplished by a restoring electromagnet 75, which is provided with a plunger 76 connected to lever 41.

The character wheels 5 are retained in their advanced position, after the operation 45 of the coöperating actuators 11 to 14 inclusive, by an individual spring tensioned stop 80. These stops are normally in a position to engage the teeth of ratchet wheels 8 to prevent springs 7 from returning the character wheels. They are all carried upon a bracket 81 pivoted to the framework on an axis 82, about which it is adapted to be rotated by a release electromagnet 83 whose armature 84 is carried by bracket 81. When 55 electromagnet 83 is energized, all of the stops 80 are removed from engagement with the corresponding ratchet wheels 8, and all of the character wheels, which have been moved from their normal position, are rotated in a direction opposite to that of the arrow until projections 90 thereon engage stops 91, which determine the normal positions of the character wheels.

If a permanent record of the indication 60 set up on the character wheels is desired,

means are provided for impressing the characters upon a suitable sheet of paper or other record medium. These means comprise an impression electromagnet 100, whose armature 102 carries an impression member 103. When electromagnet 100 is energized, impression member 103 carries a sheet of paper 104 against the character wheels. Armature 102 also carries a pivoted spring tensioned pawl 110 adapted to engage the 75 teeth of a ratchet wheel 111 secured to a paper feed roller 112. The paper sheet 104 is carried between paper feed roller 112 and a spring controlled tension roller 113, so that each time electromagnet 100 is energized 80 and deenergized the sheet of paper is advanced one step.

The current impulses for selectively controlling the operation of the apparatus hereinbefore described are transmitted over 85 a line conductor L, in characteristic groups of one or more impulses each, from an outlying station S. The transmitting apparatus may be of any desired type, being diagrammatically shown in the drawing as a 90 code impulse wheel 115 controlling the connection of a grounded source of energy 116 to line L. The impulses comprising a group follow each other in rapid succession, the intervals between groups, however, being 95 of considerably longer duration. The first impulse of the first group passing to ground through the winding of electromagnet 16 causes it to momentarily attract its armature 15. The attraction and return of armature 15 causes a reciprocating motion in all of the actuators 11 to 14 inclusive and the controllers 31 to 34 inclusive. It also causes latch 44 to be disengaged from hook 46, and spring 40 starts to rotate lever 41 and shaft 100 25 with its cams 21 to 24 inclusive in the direction of the arrow under the control of the escapement system. Since all but pawl 11 have their lugs 29 resting upon the cylindrical surfaces of the corresponding cams 110 22 to 24 inclusive, only this pawl is in a position where its hooked end can engage the teeth of ratchet wheel 8, and only the character wheel associated with pawl 11 is rotated. Lever 41 and cam shaft 25 are 115 moved in the direction of the arrows only a sufficient distance to prevent the reengagement of latch 44 and hook 46, further movement of the lever and cam shaft being prevented by the engagement of lug 35 of 120 checking pawl 31 and pin 30 of cam 21.

The other impulses, if any, of the first group arrive in such rapid succession that cam shaft 25, because of the repeated engagement of lug 35 and pin 30, is prevented 125 from rotating a sufficient distance to remove the flattened portion of cam 21 from its position beneath lug 29 of actuator 11.

The movement of lever 41 has also removed projection 52 from engagement with 130

one of the elements of switch 57, and this switch is closed preparing a circuit through a holding winding 120 of a control relay 121. Relay 121 is provided with an armature 122 adapted to coöperate with a front contact connected to a grounded source of energy 123. This relay is also provided with an energizing winding 124 and a second armature 125, connected to one terminal of the winding of electromagnet 75, the other terminal of which is connected to a grounded source of energy 126 and coöperating with a front contact connected to one terminal of the windings of release magnet 83, the other terminal of which is grounded.

During the longer no-current interval between the first and second group of impulses, while all of the actuators 11 to 14 inclusive and the controllers 31 to 34 inclusive are in their retracted position, spring 40 may rotate lever 41, and consequently cam shaft 25 and cams 21 to 24 inclusive, in the direction of the arrow until the flattened portion of cam 22 is beneath lug 29 of actuator 12. In this condition the shaft is moved a sufficient distance to remove the flattened portion of cam 21 from its position beneath lug 29 of actuator 11, and this actuator is raised so that its further reciprocation will have no effect upon its character wheel.

When shaft 25 is moved this far, the second set of impulses is timed to arrive. This set of impulses, since lug 29 of actuator 12 is above the flattened portion of cam 22, results in the movement of the corresponding character wheel only, and during the short intervals between the impulses of this group continued movement of cam shaft 25 is prevented by the engagement of lug 35 and pin 30 of cam 22.

During the longer interval between the second and third groups of impulses the cams are again rotated so that pin 30 of cam 22 passes outside of the influence of lug 35 of regulator 32, and when the flattened portion of cam 23 comes beneath lug 29 of actuator 13, the third group of impulses begins. Since, now, only actuator 13 does not rest upon the cylindrical portion of its corresponding cam, only the character wheel associated with this actuator is moved.

The action as above described continues, each character wheel being advanced as many steps as there are impulses in its associated group, and the rotation being successively transferred from wheel to wheel between groups until the last group of characteristic impulses has been transmitted. During the interval after the last group, lever 41 is moved by spring 40 a sufficient distance to allow projection 51 to close switch 55, whereupon a circuit is completed from grounded source 56, through the windings of impression electromagnet 100 to ground.

Electromagnet 100 thereupon pulls up its

armature 102, causing impression member 103 to press the paper 104 against the character wheels and pawl 110 to be advanced to engage the next tooth on ratchet wheel 111. The movement of lever 41 continues and projection 51 passes beyond switch 55 and the previously traced circuit is opened, whereupon electromagnet 100 is deenergized, the impression member 103 is retracted, and the paper feed roller 112 is advanced to move the paper.

Lever 41 still continues to move until projection 50 closes switch 53, whereupon a circuit is completed from grounded source 54 through the operating winding 124 of relay 121. Relay 121 thereupon pulls up both its armatures 122 and 125. Armature 122 completes a holding circuit for relay 121 from grounded source 123 through the now closed switch 57 and its holding winding 120. Armature 125 closes a circuit from source 126 through the windings of electromagnets 75 and 83 to ground. Electromagnet 83 attracts its armature 84 rotating bracket 81 about its axis 82, moving all of the holding pawls 80 out of engagement with the teeth of the corresponding ratchet wheels 8, whereupon all of the character wheels return to normal condition. The energization of electromagnet 75 causes its plunger 76 to move lever 41 about pivot 42 in a direction the reverse of that of the arrow. This movement of lever 41 rotates cam shaft 25 and cams 21 to 24 inclusive, independently of the escapement system, in a direction the reverse of that of the arrow until the flattened portion of cam 21 is beneath lug 29 of actuator 11. Lever 41 is now in such a position that projection 52 opens switch 57, breaking the previously traced holding circuit through holding winding 120, whereupon relay 121 releases both of its armatures 122 and 125, and the entire apparatus is in a normal condition ready to respond to a new set of signal impulses.

In the drawings, the character wheels are shown with numerals on their circumferences, but it will be readily understood that any sort of a word, character or designation may be placed thereon so that the apparatus will indicate or record any desired variety of information.

The invention claimed is:

1. An indicating apparatus comprising a plurality of indicating devices, an actuator for each said device, an operating electromagnet common to said actuators and operable by groups of current impulses, controllers for effecting the coöperation of said devices and said actuators, and means influenced by the current impulses for causing said controllers to effect the successive co-operation of said devices and said actuators.

2. An indicating apparatus comprising a plurality of indicating wheels, an actuator

for each said wheel, an operating electromagnet common to said actuators and operable by groups of current impulses, and means for successively effecting and terminating the coöperation of said actuators and said wheels to cause said electromagnet to successively rotate said wheels.

3. An indicating apparatus comprising a plurality of indicating wheels, an actuator for each said wheel, an operating electromagnet common to said actuators and operable by groups of current impulses, a cam for controlling the coöperation of each said wheel and actuator, means for rotating said cams, and a regulator for causing said cams to successively effect the coöperation of said actuators and said wheels.

4. An indicating apparatus comprising a plurality of indicating wheels, an actuator for each said wheel, an operating electromagnet common to said actuators and operable by groups of current impulses, a cam for each said actuator for effecting and terminating its coöperation with the corresponding said wheel, and a regulator active during the receipt of impulses and non-active during the intervals between groups of impulses for effecting the action of said cams.

5. A recording apparatus comprising a plurality of recording devices, an actuator for each said device, an operating electromagnet common to said actuators and operable by groups of current impulses, means operating during the intervals between groups of impulses for effecting the suc-

sive coöperation of said actuators and corresponding said devices, and an impression member coöperating with said devices to effect the production of a permanent record. 40

6. A recording apparatus comprising a plurality of recording wheels, an actuator for each said wheel, an operating electromagnet common to said actuators and operable by groups of current impulses, a cam for each said actuator for effecting and terminating its coöperation with the corresponding said wheel, check mechanism for effecting the rotation of said cams during the intervals between groups of impulses for 50 causing the successive rotation of said wheels by said electromagnet, and an impression member coöperating with said wheels to effect the production of a permanent record.

7. An indicating apparatus comprising a plurality of indicating devices, an actuator for each of said devices, an operating electromagnet common to said actuators and operable by groups of current impulses, a cam shaft, electromechanical means for rotating said shaft, a plurality of cams mounted on said shaft, said cams being adapted to control the coöperation of said devices and said actuators, and a regulator for preventing the rotation of said cams during the receipt of current impulses and for permitting their rotation during the intervals between groups of impulses. 60

In witness whereof, I hereunto subscribe my name this 18th day of June A. D., 1915. 70

BENJAMIN FREDERIC MERRITT.
